EDGAR E. PHINNEY, OF NEW YORK, N. Y., ASSIGNOR TO MONROE CALCULATING MACHINE COMPANY, OF NEW YORK, N. Y., A CORPORATION OF NEW YORK.

SPRING-BRAKE FOR GEARS.

1,208,366.

Specification of Letters Patent. Patented Dec. 12, 1916.

Application filed October 27, 1914. Serial No. 868,869.

To all whom it may concern:

Be it known that I, EDGAR E. PHINNEY, a citizen of the United States, resident of New York, in the county of New York and State of New York, have made a certain new and useful Invention in Spring-Brakes for Gears; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a top plan view partly in section, showing the invention, as applied. Fig. 2 is a section on the line 2—2, Fig. 1.

The invention has relation to improvements in calculating machines of the type shown in Letters Patent No. 1,080,245, dated December 2, 1913, having for its object the provision of an improved check spring or brake designed mainly for retarding the movement of and holding in position the intermediate gears of such machines.

The invention consists in the novel construction and combinations of parts, as hereinafter set forth.

In the accompanying drawings, illustrating the invention, the numeral 12 designates the intermediate gears, 3 designates a longitudinal rod having bearings in the end walls of the machine, and 4 is a coiled spring, fitting over and covering said rod, the rod acting as a stiffener for the spring to hold it up to the gears, the coils of the spring having engagement with the points or ends of the teeth.

The rod is hollowed out or recessed at 6, 6, opposite-each of said gears, to allow the coils of the spring to yield in the rotation of the gears, the yielding movement being substantially in the planes of the coils and at right angles to the longitudinal axis of the spring. The gears are in this way allowed to turn with proper freedom, and the rod is provided with a series of collars or projections 7, 7, between the recesses and having engagement with the inside of the coils of the spring, in order to provide the proper amount of resistance to movement of the gears.

The coils of the spring are arranged close together, in substantial contact with each

other, so that the teeth of the gears shall not penetrate between the coils.

It is required in the calculating machine that the teeth of the intermediate gears 12 shall engage the teeth of the registering wheels 13 in precise manner, and that when the intermediate gears are separately turned by the rotation of the primary wheels 5, they shall be separately checked in their turning, tooth by tooth. This is accomplished in the present case by locating the collars or projections of the stiffener rod midway between the intermediate gears, whereby yielding of the spring through rotation of one intermediate gear will not slacken the spring pressure upon the adjacent gear or gears, the yielding action of the spring being localized to the particular gear being turned.

The diameter of the coils of the spring has such relation to the diameter of the intermediate gears that the portion of the coils engaging the gears shall fit in between the teeth of the gears and shall engage the inner sides of the points or ends of the teeth of the gears to a sufficient extent to hold the gears properly. As each gear is turned, tooth by tooth, the particular portion of the spring affected will yield and cause distortion of all the coils thereof between adjacent collars or projections of the rod to a decreasing extent toward said collars, the elastic action of all of the distorted coils causing the center coil acted upon to react and engage the next or succeeding teeth.

It is designed by this invention to provide a spring brake or check practically noiseless in its working, having a greater holding power and yet offering less resistance to the turning of the gears or wheels than in other devices for the purpose.

This device also eliminates a great number of parts used in the old machine.

In order to adjust the pressure of the coiled spring upon the gears, suitable means are provided, being preferably end plates 8, 8, pivoted to end or partition walls of the machine at 9, 9, and wherein the longitudinal rod has end bearings at 10, 10, said rod working in slots 11, 11, of said walls.

A set screw 14 is threaded into a post 15 of each said wall of the machine, and has engagement with an eccentric extension 16 of each plate, to move the plate upon its

pivot and thereby to adjust the longitudinal rod and the coiled spring thereupon bodily toward or away from the gears. A very slight turn of the adjusting screw is needed, owing to the delicate contact of the spring with the gears. A headed guide post 17 is carried by each end plate and has engagement with a slot 18 of each end plate, and a locking screw 19 is employed with

10 each adjusting screw.

What I claim is:

1. In a yieldable check device, a member having a rod provided with projections spaced apart from each other, a coiled spring surrounding said rod and having the interior surfaces of certain of its coils engaged by said projections, and a member having engagement with the exterior surfaces of the coils of said springs located 15 between said projections, one of said members being movable with relation to the other member.
2. In a yieldable check device for a machine having a gear wheel, a rod supported 20 by said machine and provided with projections spaced apart from each other, and a coiled spring surrounding said rod and having the interior surfaces of certain of its coils engaged by said projections, said gear 25 wheel having engagement with the exterior surfaces of the coils of said spring located between said projections.
3. In a yieldable check device for a machine having gear wheels, a rod supported 30 by said machine and provided with projections spaced apart from each other, a coiled spring surrounding said rod and having its coils laterally in substantial contact with each other and the interior surfaces of certain of its coils engaged by said projections, said gear 35 wheels having engagement with the exterior surfaces of the coils of said spring located between said projections.
4. In a yieldable check device for a machine having gear wheels, a rod having end 40 bearings in the frame of said machine and provided with projections spaced apart from

each other and recesses between said projections, a coiled spring surrounding said rod and having its coils laterally in substantial contact with each other and the interior surfaces of certain of its coils engaged by said projections, said gear wheels having engagement with the exterior surfaces of the coils of said spring located between said projections and opposite said recesses. 55

5. In a yieldable check device for a machine having gear wheels, a rod having end bearings in the frame of said machine and provided with projections spaced apart from each other, a coiled spring surrounding said 60 rod and having the interior surfaces of certain of its coils engaged by said projections, said gear wheels having engagement with the exterior surfaces of the coils of said spring located between said projections, and means for adjusting said rod and said spring bodily toward and away from said gear wheels. 65

6. In a yieldable check device for a machine having gear wheels, a rod provided with projections spaced apart from each other and recesses between said projections, a coiled spring surrounding said rod and having its coils laterally in substantial contact with each other and the interior surfaces of certain of its coils engaged by said projections, said gear wheels having engagement with the exterior surfaces of the coils of said spring located between said projections and opposite said recesses, and means 70 for adjusting said rod and said spring bodily toward and away from said gear wheels, comprising end plates pivoted to the frame of the machine and wherein said rod has end 75 bearings, and adjusting screws for said end plates. 80

In testimony whereof I affix my signature, in presence of two witnesses.

EDGAR E. PHINNEY.
